UNITED STATES PATENT OFFICE.

DAVID KIMMEL, OF WARREN, PENNSYLVANIA.

OIL-WELL BAILER.

No. 908,680.

Specification of Letters Patent.

Patented Jan. 5, 1909.

Application filed November 30, 1907. Serial No. 404,577.

To all whom it may concern:

Be it known that I, DAVID KIMMEL, a citizen of the United States, residing at Warren, in the county of Warren and State of Pennsylvania, have invented a new and useful Oil-Well Bailer, of which the following is a specification.

The present invention relates more particularly to means for bailing oil or other liquid from wells, and the primary object is to provide novel valve mechanism which can be readily applied to and detached from the body of the bailer without the necessity of dismembering the same, said mechanism being provided with straining means which will prevent the ingress of sand, slate, or other solid substances that might interfere with the proper operation of the valve.

The preferred embodiment of the invention is illustrated in the accompanying drawings, wherein:—

Figure 1 is a vertical sectional view through the mechanism and through the lower portion of the bailer body. Fig. 2 is a horizontal 25 sectional view on the line 2—2 of Fig. 1.

Similar reference numerals designate corresponding parts in all the figures of the drawings.

The body of the bailer, designated by the reference numeral 3, is tubular in form, and may be of any suitable construction. To its lower end is secured a bottom member 4 that has an upstanding flange 5 fitted within the body and fastened thereto by rivets 6 or other suitable devices. This bottom member has a central threaded opening 7. A casing 8 is employed that has a contracted upstanding neck 9, a portion of which is threaded and is screwed into the opening 7 of the bottom member, as shown. This neck extends into the body and its upper end 10 constitutes a valve seat. The casing 8 has an interior chamber 11 and its side walls are provided with a plurality of inlet openings 12. The bottom 13 of the casing is also provided with a central opening 14.

A valve 15 of leather or other suitable material coöperates with the valve seat 10, and is secured to a vertical valve stem 16 that extends downwardly through the casing and through the bottom opening 14. The valve 15 bears against a tapered abutment nut 17 that operates in the neck 9 of said casing, while a metallic washer 18 rests upon said valve, being held in place by a suitable nut 19

threaded upon the upper end of the stem. The lower end of the valve stem carries a closure disk or plate 20 located below the casing and movable upwardly to cover the opening 14 when the valve is open, as will be evident.

The main body of the casing is provided with two outstanding ribs 21 that extend completely around it above and below the inlet openings 12. A screen 22 of any suitable material surrounds the body between the ribs 21, and covers the inlet openings.

With this structure, it will be evident that when the bailer is introduced into the well, the plate 20 striking the bottom of said well, will cause the upward movement of the stem 16 and the consequent opening of the valve. At the same time said plate will cover the opening 14 and prevent the inflow of fluid therethrough. Such fluid, however may flow freely through the openings 12 into the chamber and passing upwardly through the casing 9 will enter the bailer body. When the bailer is raised, the valve will immediately close, and at the same time, the plate 20 will uncover the opening 14. There are decided advantages for this structure. In the first place, the casing with the valve, can be readily removed and replaced so that in case repairs or renewals are necessary, the same can be made with ease and expedition. The strainer as will be evident, prevents the ingress of solid particles of sufficient size to interfere with the proper working of the valve, and this strainer is held in place and is protected by the upper and lower ribs 21 and 22, between which it is placed. The lower opening 14 and its closure 20, also are advantageous features, for while said opening is closed during the inflow of oil or liquid, when the bailer is raised, the opening 14 being uncovered, whatever liquid remains in the casing, together with any sediment that may collect in the bottom thereof, can flow freely out through said opening 14.

From the foregoing, it is thought that the construction, operation and many advantages of the herein described invention will be apparent to those skilled in the art, without further description, and it will be understood that various changes in the size, shape, proportion and minor details of construction, may be resorted to without departing from the spirit or sacrificing any of the advantages of the invention.

Having thus fully described my invention, what I claim as new, and desire to secure by Letters Patent, is:—

1. In a structure of the character described, the combination with a tubular body, of a casing depending therefrom and having lateral inlet openings and a bottom provided with an opening, a valve, a valve stem carried by the valve and extending through the bottom opening, and a closure for the bottom opening carried by said stem.

2. In a structure of the character described, the combination with a tubular body, of a casing depending therefrom and having lateral inlet openings and a bottom provided with an opening, a valve, a valve stem carried by the valve and extending through the bottom opening, and a closure plate for the bottom opening carried by the lower end of the stem and located exteriorly of the casing, said plate covering the bottom opening when the valve is opened.

3. In a structure of the character described, the combination with a tubular body, of a bottom member secured to the lower end thereof and having a threaded opening, a casing having an upstanding contracted neck threaded into the opening, said neck terminating at its upper end in a valve seat, the casing furthermore having inlet openings in its side walls and having a bottom provided with an opening, a valve co-operating with the seat, a valve stem depending from the valve and extending through the bottom opening, a closure for said bottom opening carried by the lower end of the stem and located outside the casing, and a screen covering the inlet openings.

4. In a structure of the character set forth, the combination with a tubular body, of a casing suspended from the body and having

a chamber that communicates with the interior of the body, a valve controlling said communication, said casing having lateral inlet openings in its different sides, a screen surrounding the body and covering the inlet openings, and continuous outstanding ribs projecting from the body and extending around the same, said ribs being located on opposite sides of the openings and on opposite sides of the screen, projecting beyond the latter and holding the screen against movement, besides constituting protecting devices that prevent the screen engaging the walls of the well during the movement of the structure therein.

5. In a structure of the character set forth, the combination with a tubular body, of a bottom member secured thereto and having a threaded opening, a casing comprising a chamber and a contracted neck, the latter being threaded into the opening and terminating at its upper end in a valve seat, said chamber having inlet openings in its side walls with ribs extending around the outside of the chamber on opposite sides of the opening, the casing furthermore having a bottom provided with an opening, a valve co-operating with the valve seat, a stem depending from the valve and slidably passing through the bottom opening, a closure plate for said bottom openings carried by the lower ends of the stem, and a screen surrounding the body between the ribs and covering the inlet openings.

In testimony, that I claim the foregoing as my own, I have hereto affixed my signature in the presence of two witnesses.

DAVID KIMMEJ.
